HYDRAULIC RECOIL-BRAKE.

1,063,070.

Specification of Letters Patent. Patented May 27, 1913.

Application filed October 12, 1911. Serial No. 654,353.

To all whom it may concern:

Be it known that I, FRIEDRICH SACHTLEBEN, a subject of the Emperor of Germany, and a resident of Essen-on-the-Ruhr, Germany, have invented certain new and useful Improvements in Hydraulic Recoil-Brakes, of which the following is a specification.

This invention relates to improvements in hydraulic recoil brakes for gun carriages and 10 particularly to those with variable recoil.

The object of the present invention is to provide a brake of this kind wherein a simple device for regulating the length of the recoil, by means of the elevation of the gun, 15 is supplied and so constructed, that the engagement or disengagement of the different parts of the device is directly accomplished in assembling or disassembling the carriage.

In the accompanying drawings one embodiment of the invention is represented and Figure 1 shows a side view, partly in section, of the parts in question of a gun carriage, with the gun in horizontal position and some parts broken away; Fig. 2 a detail plan view, 25 partly in section along line 2—2 of Fig. 1; Fig. 3 a rear view, partly in section along line 3—3 of Fig. 1; Fig. 4 a similar view to Fig. 1 but with gun elevated, and Fig. 5 a section along line 5—5 of Fig. 1, seen from the right 30 and drawn in larger scale.

The distinguishing feature of the present invention over others of this kind resides in the connection between the slide H and the carriage body C.

35 The gun A rests in the cradle B, which is provided with horizontal trunnions b¹ supported by bearings in the cradle C. These trunnions are part of a fork b², inclosing the cradle C. The bearings have hinged trunnion caps c¹. The piston rod e¹ of the hydraulic brake has a rotating disk G near the piston E, Fig. 1, which disk is guided by helical grooves in the brake cylinder D. The latter is connected to the gun barrel.

40 A muff F is screwed on the front end of the piston rod e¹ and the muff has a rearward extending, L-shaped arm f¹, f², provided with a pin f³ at its free end. This pin f³ engages in a groove h¹ in the aforesaid slide

45 H which groove runs obliquely to the axis of the piston rod e¹, while the slide H can be moved parallel to the axis of the piston rod e¹ in a bearing J secured to the cradle B.

50 At its rear end the slide H carries an extension bar h² into which a stud K is screwed.

Said stud reaches through a slit b³, Fig. 2, of the cradle B and enters a slit b⁴ of the fork b². The stud K has a roller k¹ at its outer end, see Fig. 5. A guide block S, secured on the carriage body C is provided with a groove s¹ in which the roller k¹ works. This groove s¹ is open at the top and runs in a vertical direction as regards the movement of the slide H when the cradle is in the level position.

When the gun barrel is horizontal, the parts will take the relative positions as shown in Figs. 1, 2, 3 and 5. The brake is then set for the longest recoil.

When the gun barrel is elevated, the slide H will partake of the elevation, but, on account of the engagement between the roller k¹ and the guide piece S, will, at the same time, be drawn toward the rear end of the cradle C, as the guide piece does not partake of the elevation of the gun barrel. The roller k¹ moves simultaneously a certain distance upward in the groove s¹. As a consequence of this displacement of the slide H, the piston rod e¹, with the piston E will be 80 turned, actuated by the pin f³ working in the groove h¹.

If the gun barrel be elevated at about 45°, the parts will take the relative position indicated in Fig. 4. The brake is then adjusted 85 for a short recoil.

To take the carriage apart, the trunnion caps c¹ have only to be opened, when the cradle can immediately be lifted out, the roller k¹ simultaneously leaving the groove s¹. The assembling of the carriage is performed with equal ease. The described device for displacing the slide H is therefore particularly well suited for such mounts that have to be taken apart during transportation 95 as for instance for mountain guns.

I claim:—

A recoil mount for guns with fluid recoil brake comprising a cradle, a cylinder within the cradle, fluid throttling means within the cylinder, a guide-way mounted within the cradle and disposed lengthwise of the same, a slide operable within the guide-way and provided with a cam-slot having connection with the fluid throttling means and means 100 connecting said slide to a part of the gun mount not partaking of the elevation movement of the barrel, said means comprising a guide groove inclined to the direction of the slide's movement and open at its upper end. 110

and an arm on said slide engaging normally
said guide groove in order to effect the auto-
matic regulation of the fluid throttling
means on the elevation of the gun barrel and
5 being detached therefrom by lifting said
cradle from the part of the gun mount not
partaking of the elevation movement of the
barrel.

The foregoing specification signed at Bar-
men, Germany, this 21st day of September, 10
1911.

FRIEDRICH SACHTLEBEN. [L. s.]

In presence of—

L. NUFER,
ALBERT NUFER.
